UNITED STATES PATENT OFFICE.

EMMA VAN GOFRE, OF KANSAS CITY, MISSOURI.

DESIGN FOR A SHOE-FASTENER.

50,006.

Specification for Design.

Patented Dec. 5, 1916.

Application filed July 6, 1915. Serial No. 38,325. Term of patent 3½ years.

To all whom it may concern:

Be it known that I, EMMA VAN GOFRE, a citizen of the United States, residing at Kansas City, in the county of Jackson and State of Missouri, have invented a new, original, and ornamental Design for Shoe-Fasteners, of which the following is a specification, reference being had to the accompanying drawing, in which—

Figure 1 is a perspective view of a shoe fastener made in accordance with my new

design. Fig. 2 is a side elevation of a shoe fastener made in accordance with my design.

I claim:

The ornamental design for a shoe fastener, as shown.

EMMA VAN GOFRE.
